J. M. BROCK

ACETYLENE LAMP

Filed June 23, 1920

INVENTOR.

John M. Brock

BY

Roger Kennedy & Campbell

ATTORNEYS.

UNITED STATES PATENT OFFICE.

JOHN M. BROCK, OF BROOKLYN, NEW YORK.

ACETYLENE LAMP.

Application filed June 23, 1920. Serial No. 391,107.

To all whom it may concern:

Be it known that I, JOHN M. BROCK, a citizen of the United States, residing at Brooklyn, in the county of Kings and State 5 of New York, have invented certain new and useful Improvements in Acetylene Lamps, of which the following is a specification, reference being had therein to the accompanying drawing.

10 This invention relates to acetylene gas lamps, and more particularly to the burner equipment thereof. Such equipment comprises, generally, a burner tube projecting forwardly from the gas chamber of the 15 lamp, a burner tip secured to the outer end of the tube and formed with the usual gas-orifice, and a cap surrounding the burner tip and constructed to protect the gas flame from strong drafts of air, water, etc., (see 20 the Brock Patent No. 1,269,047). In lamps in most general use, the burner tip (made of lava and of cylindrical form) is driven tightly into the outer end of the burner tube, while the protective cap (made of 25 metal and machined to form) is screwed upon the end of the burner tube so as to surround the burner tip, such cap incidentally serving to hold the lamp reflector in place upon the burner tube. As the parts 30 are thus constructed and arranged, the protective cap is comparatively expensive to manufacture, due to its particular form and the considerable number of machining operations required, and besides it is quite difficult to remove the burner tip for cleaning 35 or replacement, and especially without the use of tools, which frequently damage or fracture it in the process.

40 The present invention is intended to overcome the foregoing objections, and contemplates certain improvements in the construction and arrangement of the several parts, whereby they may not only be manufactured at materially less cost than heretofore, but 45 also assembled and disassembled with greater ease and facility, and this without requiring the use of any extraneous tools for that purpose. To these ends, specifically, it is proposed to make use of a reflector 50 which is screwed upon the outer end of the burner tube, and to employ a lava burner tip comprising a neck portion driven tightly but detachably into the open end of the burner tube and an enlarged head portion 55 located beyond such end of said tube, the arrangement being such that by unscrewing

the reflector, the burner tip will be gently yet positively pushed from its seat in the burner tube, thereby obviating any danger of fracturing or damaging the tip in its removal. In providing for this arrangement, the protective cap is applied directly to the burner tip, being formed with elastic fingers which fit over the enlarged head portion of the burner tip and which act by their frictional engagement therewith to hold the cap in place; and to insure the retention of the cap upon the burner tip, the latter is formed in its outer surface with a peripheral groove to engage ribs or flanges projecting inwardly 60 from the elastic fingers, such engagement being permitted and effected by the yielding of the elastic fingers as the cap is forced into position. The cap is also formed at or near the base of the elastic fingers with 65 an interior annular rib or flange which engages the forward face of the enlarged head portion of the burner tip when the cap is applied thereto and thus positions and maintains the parts in their proper cooperative 70 relation. As so formed and arranged, the protective cap may be, and in actual practice is, produced by stamping out a blank from a thin sheet of metal (e. g. brass) and then turning or pressing the blank into the 75 required form, so that the cost of manufacture of the cap is reduced to a minimum.

In the accompanying drawings:

Fig. 1 is a side elevation, partly in section, of a lamp equipped with the improved 80 parts, and showing by the dotted lines the manner in which they are removed.

Fig. 2 is an elevation of said parts in un-assembled condition, but with the protective 85 cap applied to the burner tip; and

Fig. 3 is a perspective view of the burner tip and protective cap in separated condition.

The lamp A is provided as usual with the reflector B, the burner tube C, the burner tip 100 D, and the protective cap E, the latter covering the burner tip and constructed to form a flame-surrounding chamber into which the burner orifice opens. The lamp itself may be of any suitable or well-known construction, such for instance as shown in the Brock Patent No. 1,193,985, the present invention being concerned only with the remaining elements which will now be described in detail.

Referring first to the reflector B, it is provided with a centrally located sleeve por-

tion B¹ adapted to fit over the outer or protruding end of the burner tube C. In the present instance, however, and for reasons to be pointed out, the sleeve portion B¹ is formed on its interior with screw threads adapted to cooperate with corresponding screw threads formed on the exterior of the burner tube. Hence, the reflector B may be freely applied or removed by merely screwing it to or unscrewing it from the burner tube.

The burner-tip D is preferably made of ordinary lava and is formed with the customary gas outlet or orifice D¹. In the embodiment illustrated, the burner tip comprises a conical neck portion D² and an enlarged cylindrical head portion D³, although the particular shape of these portions may be otherwise if desired. When the parts are in assembled condition (as in Fig. 1), the neck portion D² is seated tightly in a corresponding bore formed in the outer end of the burner tube C, while the enlarged head portion D³ is located beyond such end of the tube and in front of the reflector B, it being noted that the diameter of the head portion is greater than the interior diameter of the sleeve portion B¹. As a result of this arrangement, when it is desired to remove the burner tip for cleaning or replacement, this may be done merely by unscrewing the reflector B, which by its engagement with the rear face of the enlarged head portion D³ gently but positively pushes the tip from the burner tube (see dotted lines in Fig. 1). This arrangement is very advantageous, in that it not only enables the burner tip to be quickly and easily removed, but it obviates any possible damage to the tip in its removal. It will be understood of course, that in removing the burner tip as just indicated, the reflector B does not need to be unscrewed entirely from the burner tube.

Referring now to the protective cap E, it is formed in its front face with the central opening E¹ arranged in alignment with the burner orifice D¹ and through which the flame may extend; and it is also formed in its front face with the further smaller openings E² arranged concentrically about the central opening E¹ for the admission of air to the interior chamber to support combustion within said chamber. The purpose of these cap openings is fully set forth in the Brock Patent No. 1,269,047 above mentioned and need not therefore be discussed further here. In accordance with the present invention, the cap E, instead of being screw-threaded to the burner tube C as in prior constructions, is applied directly to the burner tip D, being formed at its rear with elastic fingers E³ produced by cutting or slitting the cylindrical portion of the cap, as at E⁴. These elastic fingers (Figs. 1 and 2) fit over the enlarged head portion D³ and confine the

cap in place by their frictional engagement therewith. However, to insure the more positive retention of the cap upon the burner tip, it is preferred to construct these parts so as to interlock with each other when attached. To that end, in the embodiment illustrated, the head portion D³ is formed in its outer surface with a peripheral groove D⁴ while the elastic fingers E³ are formed on their inner faces with circumferentially extending ribs on flanges E⁵, which may be conveniently produced by pressing or indenting. By reason of this construction, when the cap is applied to the burner tip, the ribs E⁵ in passing over the enlarged head portion D³ spread the elastic fingers E³ outwardly and maintain them in this condition until the ribs reach the peripheral groove D⁴, when the fingers because of their elasticity act immediately to snap the ribs into the groove, thus effecting the interlocking of the parts. Of course, in removing the cap from the tip, the elastic fingers yield outwardly to permit the ribs to be disengaged from the groove. It will be seen therefore that, while the cap may be readily applied to and removed from the burner tip as desired, it is held firmly in position thereon when in use so as to withstand any rough usage to which the lamp is subjected without danger of being knocked or jarred off.

It is important that the protective cap when applied to the burner tip be properly located thereon so as to provide a certain amount of air space between its front face and that of the burner tip. While the engagement of the ribs E⁵ in the groove D⁴ would probably be sufficient, it is preferred to provide other means to insure this result. Accordingly and by way of example, the cap E is formed with a further interior annular rib or flange E⁶ (as by the pressing or indenting of the collar portion of the cap), which rib is located at the base of the elastic fingers E³ and in such position that, when the cap is forced over the burner tip, it engages the front face of the head portion D³ at or about the instant the ribs E⁵ reach the groove D⁴. The rib E⁶ thus acts as a stop to prevent the cap from being pushed beyond its proper position on the burner tip when applied thereto, serving also as a seal to prevent the escape of air from the chamber within the cap.

It is believed the manner in which the parts are assembled and disassembled will be entirely clear from the foregoing description. However, to recapitulate, in assembling the parts, the reflector B is first screwed on to the burner tube C (see Fig. 2), then the lava burner tip D is driven tightly into the protruding end of the burner tube, (as by tapping the tip with a wooden mallet), and thereafter the protective cap E is forced over the burner tip by hand pressure.

In removing the tip, the reflector B is unscrewed from the burner tube, and pushes the tip from its seat therein, see dotted lines in Fig. 1. The detachment of the cap from the burner tip may be readily effected by gripping it with the fingers and drawing it from the cap, which may be done either before or after the tip is removed from the burner tube.

Some of the advantages of the improved arrangement have already been mentioned. It is particularly noted that the parts are extremely simple and can be made at small cost and fitted together without the slightest difficulty or delay and without involving any radical alteration in the existing parts, which may therefore be manufactured in the usual way. In addition, the arrangement is strong, durable and compact, and is capable of ready assemblage and disassembly to permit cleaning or repair. These and other advantages will be apparent to those skilled in the art. However, in its broader aspects, the invention is not limited to the precise construction shown and described, as many changes may be made in the details thereof without departing from the spirit of the invention or sacrificing its chief advantages. Generally speaking, it is to be understood that the invention is not limited to any specific form or arrangement except in so far as such limitations are specified in the claims.

Having thus described my invention, its construction and mode of operation, what I claim is as follows:

1. A lamp comprising a burner tube provided with an internal burner-receiving surface; a burner having a securing portion including a surface adapted to conform with the internal burner-receiving surface of the tube and to be disposed within the tube; said burner having a portion constituting a shoulder which extends beyond a marginal edge of the burner tube when the burner is disposed therein; and a member disposed on the outer surface of the burner tube back of the shoulder on the burner, said member

being adapted to engage the shoulder on the burner when being removed, whereby separation of the member and the burner tube will also effect removal of the burner from within the tube.

2. A lamp comprising a burner tube provided with an internal burner-receiving surface; a burner having a body; a securing portion on the body, said securing portion having a surface adapted to engage with and be disposed on the inside of the burner tube to attach the burner to the tube; a shoulder on the burner in proximity to the securing portion and extending beyond a marginal edge of the burner tube when the burner is attached to the tube; a member detachably disposed on the outer surface of the burner tube back of the shoulder on the burner, said member being adapted to engage the shoulder on the burner when the member and burner tube are disconnected and remove the burner from the tube; and a cap having a resilient securing portion adapted to engage a portion of the burner to detachably attach the cap to the burner, said cap and burner being removable as a unit when the member and burner are disconnected and the cap being removable from the burner without disconnecting the burner from the tube.

3. In an acetylene lamp, the combination of a burner having a burner orifice, and a protective cap covering the burner and constructed to form a flame surrounding chamber into which the burner orifice opens, said protective cap being fitted over the burner and formed with separate elastic fingers adapted to yield outwardly in permitting the application or removal of the cap, and the said cap being further formed with a rib or flange adapted to engage the forward face of the burner to locate and maintain the cap in proper position with reference thereto.

In testimony whereof I have affixed my signature hereto.

JOHN M. BROCK.
